UNITED STATES PATENT OFFICE.

BENJAMIN Y. CONKLIN, OF BROOKLYN, NEW YORK.

FOOT-REST FOR REGISTERS.

SPECIFICATION forming part of Letters Patent No. 231,402, dated August 24, 1880.

Application filed March 19, 1880. (No model.)

To all whom it may concern:

Be it known that I, BENJAMIN Y. CONKLIN, a citizen of the United States, residing at the city of Brooklyn, in the county of Kings, State of New York, have invented a new and useful Improvement in Foot-Rests for Hot-Air Registers, which improvement is fully set forth in the following specification and accompanying drawing, in which the figure is a perspective

10 view of the foot-rest embodying my invention.

This invention relates to foot-rests which are attached to registers; and it consists in the construction, combination, and arrangement of the same and the attaching devices, substantially as hereinafter particularly set forth.

Referring to the drawing, A represents a horizontal plate or piece, from the side ends of which rise vertical pieces B B, and C represents a horizontal piece supported on the top 20 of the pieces B B, the several parts being constructed of wood or metal properly secured to each other or cast in one piece, the whole forming an open frame or foot-rest, which may be of the size of a hot-air register (shown in dotted lines) or larger or smaller than the same, as desired, so that when said frame is applied to the register all or some of the heat will pass through it.

In order to secure the rest to the register, I 30 provide, at the upper ends of the side pieces, B, hooks D D, which may be of various forms. In the present case they are hinged or slotted and connected to said side pieces, B, by means of bolts E E, so as to be tightened against the 35 walls of open-work of the register; or they may be arranged horizontally, in order to engage with the upright bars or sliding registers. The register may also be formed with eyes to receive the hooks of the rest, or the latter have 40 eyes for engagement of hooks connected to the register; or the rest may be cast in one or more pieces with the stationary frame of the register. Furthermore, the side pieces, B, or bottom plate,

A, have rearward-projecting lugs F, which rest on the lower portion of the register and are secured to or formed with said pieces or plate. 45

The operation is as follows: When the feet are to be warmed they are placed on the plate A as a support, and so are reached by the heat from the register, they being sustained in a comfortable, convenient, and non-fatiguing manner, and without liability of slipping. 50

The fastenings D prevent separation of the rest from the register, and the lugs F serve to prevent downward displacement or shifting of the rest, so that the weight of the feet and rest is transferred to the register, it being also noticed that the rest is elevated above the floor of the apartment, whereby there is avoided the employment of supports on the floor, and there 60 is a saving of the room thereof.

The top piece, C, serves as a deflector and directs the heat within the confines of the rest; but, if desired, the latter may be smaller than the register, whereby some of the heat may pass 65 above or below the rest. The deflector may also provide an additional support for the feet when it is not desired to place them on the bottom plate, A.

It will also be noticed that the rest protects 70 the wall or paper surrounding the register.

Having thus described my invention, what I claim as new, and desire to secure by Letters Patent, is—

1. The combination, with bottom piece, A, 75 and side pieces, B, of slotted fastening D, clamp-screw E, and beveled lower support, F.

2. In combination with bottom piece, A, and side pieces, B, and fastening devices for attaching them to the outside of a register, the 80 deflector C, supported by said pieces, substantially as set forth.

B. Y. CONKLIN.
